Primary Examiner — Christian P. McLean(74) *Attorney, Agent, or Firm* — Brandon V. Zuniga; James R. Gourley; Carstens & Cahoon, LLP(57) **CLAIM**

The ornamental design for a display screen with transitional graphical user interface, as shown and described.

DESCRIPTION

FIG. 1 is a front view of a display screen with transitional graphical user interface showing my new design; FIG. 2 is an enlarged view thereof with a first image shown in FIG. 1; and,

FIG. 3 is an enlarged view thereof with a second image. The outermost broken lines illustrate the environment of the design and form no part of the claim. The remaining broken lines illustrate portions of the graphical user interface that form no part of the claimed design.

The appearance of the animated image sequentially transitions between the images shown in FIGS. 2 through 3. The process or period in which one image transitions to another forms no part of the claimed design.
